UNITED STATES PATENT OFFICE.

SILAS R. SKAGGS, OF RICHLAND SPRINGS, TEXAS.

FARM-GATE.

1,242,255.

Specification of Letters Patent.

Patented Oct. 9, 1917.

Application filed September 25, 1916. Serial No. 122,112.

To all whom it may concern:

Be it known that I, SILAS R. SKAGGS, a citizen of the United States of America, residing at Richland Springs, in the county 5 of San Saba and State of Texas, have invented certain new and useful Improvements in Farm-Gates, of which the following is a specification, reference being had therein to the accompanying drawing.

10 This invention relates to a farm gate and has for its principal object the production of a simple and efficient means for either opening or closing the gate upon the pulling of an operating cable.

15 Another object of this invention is the production of a farm gate wherein the opening and closing elements are arranged so as to positively and automatically lock the gate in either an open or closed position.

20 A still further object of this invention is the production of a farm gate wherein the opening and closing elements are pivotally mounted upon their supports so as to pivot and also swing, thereby correctly moving 25 for permitting the gate to be opened or closed when desired.

With these and other objects in view this invention consists of certain novel combinations, constructions, and arrangements of 30 parts as will be hereinafter fully described and claimed.

In the accompanying drawing:

Figure 1 is a side elevation of the complete farm gate as constructed in accordance 35 with this invention and shown in a closed position.

Fig. 2 is a top plan view of the farm gate as constructed in accordance with this invention, the pulley standard being broken away.

40 Fig. 3 is a detail perspective view of the cam link.

Fig. 4 is a detail perspective view of the operating arm.

Fig. 5 is a fragmentary vertical section 45 taken on the line 5—5 of Fig. 1.

Fig. 6 is a fragmentary vertical section taken on the line 6—6 of Fig. 2.

Fig. 7 is a section taken on the line 7—7 of Fig. 2.

50 Fig. 8 is a section taken on the line 8—8 of Fig. 2.

Fig. 9 is a detail sectional view of a portion of the pulley standard.

Referring to the accompanying drawings 55 by numerals it will be seen that the gate 1 is connected by means of any suitable

hinges 2 to the supporting standard 3, thereby pivotally supporting the gate. It is, of course, obvious that the gate, hinges, and standard may be of any suitable construction, for the present invention relates specifically to the construction of the opening and closing means.

The bracket 4 which is of a substantially inclined construction as shown in Fig. 8, 60 has plates 5 extending from its end portions so as to permit the plates 5 to rest against the standard 3 and the pulley standard 6. Securing screws or similar means 7 may then be passed through the plates 5 65 and into engagement with the supporting standard 3 and the pulley standard 6 for fixedly retaining the bracket 4 in a desired set position. The swivel bolt 8 passes through the bracket 4 and has a flat body 9 70 formed upon its upper end, while the lower end of the body is adapted to support the nut 10. Thus, it will be seen that the body 9 will rest upon the upper surface of the bracket 4 while the nut 10 will rest upon 75 the lower surface for holding the bolt against accidental displacement, although, of course, permitting the bolt to pivot or rotate when necessary. Parallel strips 11 are fixedly mounted in any suitable manner upon the upper portions of the gate 1 and these strips 11 also have a bolt 12 passing therethrough and extending in a horizontal plane. This bolt 12 is also provided with a body 13 formed upon one end, while 80 it carries the nut 14 upon its opposite end, thus causing the bolt 12 to be pivotally supported upon the strips 11 in a manner similar to the mounting of the bolt 8 upon the bracket 4. The cam link 15 is a comparatively long structure which has parallel ears 16 extending from one end thereof in which are formed aligned openings 17. At the opposite end of this link 15 there is formed an offset lip 18 having an opening 19. The ears 16 embrace the body 13 of the bolt 12, as shown in Figs. 1 and 5 and at this time the openings 17 of the ears 16 will register with the opening 17' formed in the body 13. The retaining bolt 20 95 passes through the openings 17 and 17' so as to receive the nut 20' whereby the bolt will be held against accidental displacement. Thus, it will be seen that the bolt passing through the openings 17 of the ears 16 100 will permit the link 15 to be swung to either side, while the pivoting of the bolt 12

105

110

upon the strips 11 will permit the link to be moved in a vertical plane when necessary.

The operating arm 21 is elongated and carries a weight 22 upon its outer end. This arm 21 is enlarged as shown at 23 adjacent its inner end so as to have the yoke 24 in which is formed alined openings 25 formed integral thereon. The enlarged portion 23 is also provided with an opening 26, as shown in Fig. 4, for purposes to be hereinafter set forth. The yoke 24 embraces the body 9 of the bolt 8, as shown in Fig. 2, at which time a rivet or other securing means 27 is passed through the openings 25 of the yoke 24 and through the body 9, thus pivotally securing the inner end of the operating arm 21 upon the swivel bolt 8. By the mounting of the arm in this manner it will be seen that the arm may be either moved in a vertical plane by pivoting upon the rivet 27, or moved sidewise by the swinging or pivoting of the swivel bolt 8 upon the bracket 4. At this time the offset lip 18 of the cam link 15 is positioned so as to rest upon one side of the operating arm 21, as shown in Fig. 2. By having the lip 18 offset with respect to the enlarged portion of the cam link 15 it will be seen that sufficient space is provided between the greater portion of the link and the arm for the reception of the weight 22. A pivot member, such for instance as a rivet 28 is passed through the opening 26 of the enlarged portion 23 and the opening 19 of the offset lip 18, thereby pivotally connecting these elements together. A substantially inverted U-shaped locking clip 29 is carried by means of the rivet 30 in a fixed position upon the arm 21 and this clip 29 is provided with an outwardly bent end 31 for assisting in directing the clip over the cam link 15 when the gate is in a closed position.

The pulley standard 6 is provided with a head piece 32 upon which is carried pulleys 33 although, of course, it is obvious that a double pulley may be employed if so desired. The auxiliary pulley standards 34 are carried at considerable distances to either side of the gate and standards thereof and these auxiliary standards in turn have heads 35 carrying pulleys 36. The cables 37 are secured to the eye 38 formed upon the outer end of the weight 22 and then pass up over the pulleys 33 carried by the head 32 of the pulley standard 6. The cables 37 then extend to pass over the pulleys 36 so as to hang down as shown in Fig. 1 and carry weights 39. When this device is in use and the gate is in a closed position it will be seen that the operating arm 21 and the cam link 15 will extend in substantially the same horizontal planes, the downward movement of each element being limited by the fitting of the clip 29 over the link 15. At this time it will be seen that the gate 1 will be positively held in a closed position for any tend-

ency toward opening the gate 1 will cause the strain to be imparted directly from the bolt 12 to the bolt 8 as the positioning of the arm 21 and the link 15 will constitute a dead center between the two bolts, thus 70 positively holding the gate closed. When it is desired to pass through the gate the cables 27 may be pulled over the pulleys 33 and 36, thus causing the weight 22 to be lifted and in turn the outer end of the operating arm 21 swung upwardly. As this arm 21 is swung upwardly it will draw upon the cam link 15 connected to the body 13 of the bolt 12. It is obvious that as this arm is swung upwardly and the link 15 is pulled 80 by the arm 21 the distance between the pivot points of the arm and the link will be shortened considerably and necessarily the gate 1 will be opened. As the gate opens the swivel bolt 8 will turn so as to allow the 85 arm 21 to swing to one side, while the pivot rivet 27 will permit the arm to be swung upwardly. Furthermore, the upward movement of one end of the cam link 15 will cause the bolt 12 to pivot upon the strips 11, 90 while the bolt 20 will permit the cam link to have a slight side movement as the gate is being swung. It is, of course, obvious that if it is desired to retain the gate in a locked open position a quick but strong pull or jerk 95 should be imparted to one of the cables which action will cause the arm 21 to be lifted at its outer end so that the momentum imparted to the weight 22 will cause the weight to be moved past the dead center when swung 100 to a vertical position so that as the weight falls rearwardly beyond the rear portions of the bracket 4 it will continue to move downwardly until it reaches a substantially horizontal plane extending across the top of the 105 bracket 4. Thus, it will be seen that a substantially dead center with respect to the pivot connections of the arm and link will be maintained thus holding the gate in an open position and preventing its accidental 110 closing. Of course, this action will swing 115 the lip 18 of the cam link 15 considerably over the rear portions of the bracket 4 to cause the shortening of the cable. When it is desired to close the gate either one of the cables may be given a sharp jerk or pull, thus swinging the weighted end of the arm upwardly so that the momentum of the weight will swing the weight forwardly and the continued pivotal movement of the arm 120 21 will push or shove upon the cam link 15 for causing the link to push against the bolt 12, thus moving the gate to a closed position. As the gate moves to a closed position the clip 29 will move over the cam link 15 thus 125 holding the operating arm 21 and the cam link 15 in alinement with each other, presenting the same dead center with respect to the pivot points for holding the gate in a locked closed position.

From the foregoing description it will be seen that a very efficient positively operating farm gate has been produced, wherein the connections of the cam link and operating arm will cause the gate to either move to an open or closed position as the arm is being moved by the operating cables. Furthermore, it will be seen that after the movement of the gate in either direction is stopped the extension of the link and arm in substantially horizontal planes will present substantially dead centers with respect to the pivot points for holding the link and arm against movement, which action will either cause the gate to be locked in an open or closed position.

What is claimed is:—

1. In a device of the class described, the combination of a gate, means for pivotally supporting said gate, a bolt pivotally mounted upon said gate, said bolt having a body formed thereon, a cam link having parallel ears, said ears embracing said body, a bolt passing through said ears and said body for pivotally mounting said cam link upon said body, whereby said cam link may be free to move in either a vertical plane or to one side, an operating arm pivotally mounted upon said cam link, means for supporting said operating arm, said operating arm being adapted to swing for drawing or pushing upon said link according to the direction in which the arm is being swung, whereby said gate may be either opened or closed, means for limiting the downward movement of said arm in either direction, whereby when the movement of the arm in either direction is stopped it will remain in the same horizontal plane as said cam link, thus positively holding the gate in a locked position.
2. In a device of the class described, the combination of a gate, means for pivotally supporting said gate, a bracket comprising a substantially inclined U-shaped body, a plate extending from each end of said body

and secured to said means, and a post whereby said bracket will be supported, a swivel bolt extending through said body of said bracket, said swivel bolt having a body, an operating arm provided with a yoke 50 formed upon one end, said yoke embracing the body of said swivel bolt, means for pivotally connecting said yoke to the body of said swivel bolt, thereby pivotally mounting said arm and permitting the same to move 55 in either a vertical plane or to one side, a cam link pivotally connected to said operating arm, the remaining end of said cam link being pivotally connected to said gate, whereby as said arm is swung it will draw 60 or push upon said cam link according to the direction in which the arm is being moved, thereby opening or closing said gate, and means for limiting the swinging movement of said arm in either direction whereby 65 when the movement of the arm is stopped the arm will extend in substantially the same plane as said link for constituting dead centers between the pivot points and thus hold the gate in either an open or closed position. 70

3. In a device of the class described, the combination of a gate, means for pivotally supporting said gate, a bolt pivotally mounted upon said gate, said bolt having a body formed thereon, a cam link having 75 parallel ears, said ears embracing said body, a bolt passing through said ears and body for pivotally mounting said cam link upon said body, whereby said cam link may move in either a vertical plane or to one side, an 80 operating arm pivotally mounted upon said cam link, means for pivotally supporting said operating arm, said operating arm being adapted to swing for drawing or pushing upon said link, whereby said gate may 85 be either opened or closed.

In testimony whereof I hereunto affix my signature.

SILAS R. SKAGGS.
